(57) **CLAIM**

I claim the ornamental design for an automotive door pocket insert, substantially as shown.

DESCRIPTION

FIG. 1 is a perspective view of the automotive door pocket insert taken from the top of the design.

FIG. 2 is a bottom perspective view of the design of FIG. 1.

FIG. 3 is a front elevational view of the design of FIG. 1.

FIG. 4 is a rear elevational view of the design of FIG. 1.

FIG. 5 is an end elevational view as taken from the left of FIG. 1.

FIG. 6 is an end elevational view as taken from the right of FIG. 1.

FIG. 7 is a top plan view of the design of FIG. 1; and,

FIG. 8 is a bottom plan view of the design of FIG. 1.
